Inventor:

Morgan Dyer

UNITED STATES PATENT OFFICE.

MORGAN DYER, OF ELMIRA, NEW YORK.

DESIGN FOR A STEP AND HITCHING-POST.

Specification forming part of Design No. 4,057, dated May 24, 1870.

To all whom it may concern:

Be it known that I, MORGAN DYER, of Elmira, in the county of Chemung and State of New York, have invented a new and original Design for a Combined Step and Hitching-Post; and I do hereby declare that the following is a full, clear, and exact description thereof, which will enable others skilled in the art to make and use the same, reference being had to the accompanying drawing, forming part of this specification.

The figure is a perspective view of a combined step and hitching-post illustrating my improved design.

My invention has for its object to furnish an improved design for a combined step and hitching-post, making it more ornamental and pleasing in appearance; and it consists in the design herein shown and described.

A is the standard, which is curved or bent, bringing the upper step, B, farther in the rear of the lower one, C. The upper step, B, and lower step, C, are formed and ornamented as shown in the figure.

D is a flange formed upon the lower end of the standard A, as shown in the figure.

E is the hitching-post, which is formed and ornamented as shown in the figure.

I claim as my invention—

The design for a combined step and hitching-post, herein shown and described.

MORGAN DYER.
